UNITED STATES PATENT OFFICE.

EMIL VOLKERS, OF BERLIN-LANKWITZ, GERMANY.

OSCILLATING PENDULUM.

Application filed February 3, 1922. Serial No. 533,959.

To all whom it may concern:

Be it known that I, EMIL VOLKERS, a subject of Germany, residing at Berlin-Lankwitz, Germany, have invented certain new and useful Improvements in Oscillating Pendulums; of which the following is a specification.

This invention relates to oscillating pendulums; and it proposes certain improvements, hereinafter fully described, by virtue of which an increased efficiency is obtained, together with decreased cost of construction.

An embodiment of the invention is illustrated in the accompanying drawing in which Figures 1 and 2 are, respectively, a front elevation and a side elevation showing the improved pendulum in use.

Referring more particularly to the drawing, the pendulum comprises two separate sections or members 1 and 2; the upper section 1 having the form of a nickle-steel rod, and the lower section 2 consisting of a nickle-steel wire, the lower end of which has attached to it the weight 3. The latter is given a shape such that its air resistance is the same at all points, i. e., a cylinder or sphere, by preference. The rod 1 is attached to a pivotal support 5 by means of a suspension spring 4, said support 5 being suitably mounted in the frame or cage 6 of the clockwork; and the usual fork 7 is employed and is engaged with said rod.

The portion of a pendulum which is below the fork, is subjected almost exclusively to traction, as is well understood; and it is to be observed that in the present construction this portion consists of the wire 2. The diameter of the wire is chosen so that the wire will be held taut by the pulling force of the weight 3; and that fact, together with the high mechanical strain to which the wire is subjected, will prevent the occurrence of jerks to compensate for interior tension. This absence of jerks will be conducive to a steadiness of compensation which is practi-

cally impossible to obtain when the weight-supporting member of the pendulum takes the form of a single nickle-steel rod, even though such rod has been subjected to long tempering; and furthermore, the small amount of nickle steel necessary for the construction of the pendulum wire will render the latter almost insensible to magnetic influences—in which respect it is distinguished from the ordinary pendulum rod—and will permit it to be manufactured at comparatively low cost and, hence, to be installed in cheaper grades of clocks than has heretofore been possible.

A further advantage of the present construction, is that the center of oscillation almost coincides with the center of gravity of the weight, for which reason the pendulum may be made shorter than usual. Isochronism is promoted by the flexion or bending of the wire, which cannot take place with the ordinary rod; and since this flexion or bending will increase with the increasing amplitude of the swing, a corresponding decreasing of the mathematical length of the pendulum will result, as is required for isochronism.

I claim as my invention:—

1. An oscillating pendulum, comprising a suspension spring; a weight; and a connection between the spring and the weight consisting of a rigid upper member, and a freely flexible lower member structurally separate from the upper member and attached to the lower end thereof.

2. An oscillating pendulum, comprising a suspension spring; a rod suspended therefrom; a wire suspended from the lower end of the rod; and a weight suspended from the lower end of the wire.

In testimony whereof I have affixed my signature.

EMIL VOLKERS.
